CLAIM

The ornamental design for a seat, as shown and described.

DESCRIPTION

FIG. 1 is a right side perspective view of a seat showing our new design in the form of a sofa;
FIG. 2 is a left side perspective view;
FIG. 3 is a rear perspective view thereof;
FIG. 4 is a right side perspective view of a seat showing our new design in the form of a love seat;
FIG. 5 is a left side perspective view thereof;
FIG. 6 is a right side perspective view of a seat showing our new design in the form of a chair; and,
FIG. 7 is a left side perspective view thereof.
The only difference for the rear view of the love seat and the chair from the sofa as shown is a matter of length thereof. The broken lines shown on the cushion members represent stitching. The broken line showing of leg members are for illustrative purposes only and form no part of the claimed design.
